UNITED STATES PATENT OFFICE.

LOUIS EUGÈNE CLÉMENCET, OF PARIS, FRANCE.

WASHING MACHINE.

Application filed May 6, 1926, Serial No. 107,153, and in France May 12, 1925.

The object of this invention is to provide an improved machine which will buck or scald, wash and rinse material by causing jets of steam and water or other boiling liquid to impinge against the same, such machine being adapted to treat or wash objects or material of various kinds, especially linen.

In the accompanying drawings:

10 Figure 1 is a vertical sectional view of one form of machine;

Fig. 2 is a horizontal section thereof;

Fig. 3 is a section at right angles to Fig. 1;

15 Fig. 4 is a vertical cross-section of a modification;

Figs. 5 and 6 are similar views of further modifications;

Fig. 7 is a fragmental vertical cross-section, showing a double bottom;

20 Figs. 8, 9 and 10 are cross-sections of double bottoms with siphons;

Figs. 11 and 12 are cross-sections of double bottoms with valves.

25 Figs. 13, 14 and 15 are longitudinal sections of injecting devices.

A drum 1 (Figs. 1, 2 and 3) has its surface wholly, or partly perforated with holes 2, and is also provided with an opening 3 for the admission of a subsequently-described injector; such opening 3 being closable at will by means of a door 4, or other suitable contrivance. 5 indicates the door for the drum. One or more baffles 6 of suitable form may be arranged inside the drum and may themselves be perforated with holes 7.

30 The drum is here shown as cylindrical, or substantially so, though it may have any other desired shape, and it is fitted with two trunnions 8 adapted to rotate in bearings or 40 supports 9 rigidly connected to an outer vessel or container 10 wherein said drum is arranged and in which it is rotated by means of a suitable device.

45 Container 10, which likewise may be of any desired form, is provided with a double bottom 11 that is fixed or removable. This element is preferably of conical or concave shape and is perforated at its lower portion with holes 12, while its top is shaped to form a neck or throat 13 on which is fitted a removable injector 14 of suitable form. This injector extends upward to about the upper portion of the drum, and it is provided either at its upper end or at some other point with jet 50 holes or apertures 15, the top of said injector being closed by a plate or disk 16.

In case the bottom member or cone 11 is removable, it may simply rest on the bottom wall of the container, or it may be detachably connected thereto by any suitable means. As 60 an example, a device adapted to permit such removable attachment has been illustrated, comprising two or more studs 17 secured to the container near its bottom for engagement in inclined slots 18 formed in the peripheral portion of the bottom member or cone. In order to fix said member in position, it is merely necessary to bring slots 17 opposite studs 18 and then turn it slightly to make the studs catch. The aforesaid slots may, if 65 desired, take the place of the holes 12.

The outer vessel or container 10 may be provided with a spout 19 for filling and emptying purposes, which may itself be fitted with a lid 20 to prevent escape of liquid during operation of the machine; and said container may also be equipped with handles 21 and with a drain cock 22 and an overflow 23, and may have a cover 24, the overflow 23 being closable by a suitable plug or the like. The cover 24 may be provided with handles 25, and by turning it upside down it is rendered available to receive the material before and after washing. As shown in Fig. 1, the handles 25 are so set as to extend in the proper direction when the cover is placed on its bottom.

In operation, the outer vessel or container 10 is charged with the washing or other liquid and then is placed on a suitable heater. The 90 liquid within the bottom member or cone 11 soon starts to boil and the steam thereby evolved rises and escapes through the neck or throat 13. With the exception of a very small portion, mentioned later on and which escapes through the openings 12 and 18, no outlet for the steam other than said neck is provided; in fact, in order to escape through the aforesaid openings it would be necessary for the steam to lower the level of the liquid 95 in the cone by forcing it far enough down to uncover said openings which are normally sealed by the liquid and to do that it would have to overcome the pressure of the column of liquid *a*. The steam which can escape through openings 12 and 18 is merely the 100 small amount which is produced directly beneath or in the immediate vicinity of these openings; and such amount does not interfere with the operation of the machine, being, indeed, counteracted by the liquid which circulates in the opposite direction (indicated 105 110

by arrows *d*) through the very same openings 6 to pass from the container into the cone, as hereinafter explained. It should be noted, moreover, that the operation would remain the same if the whole of the liquid in the container, and in particular the part outside the cone 11, were set boiling by the heater at the same time as the part within said cone.

The steam ascends, as shown, through the cone throat 13 into the injector 14, carrying with it part of the liquid. This mixture of steam and liquid, on reaching the top plate 16 of the injector, is discharged into the drum through the apertures or jet holes 15 and spreads or expands into the form of a curtain *c* which showers upon the material under treatment and works its way therethrough, finally escaping through the lower holes 2 of the drum. Replacing the liquid just evacuated from the cone, some liquid enters the latter from outside through the openings 12 and 18 and, always mixed with steam, is carried along, in its turn, through the parts 13 and 14 and is ultimately sprayed through apertures 15.

According to the activity of the boiling, the spraying or sprinkling is either intermittent or continuous; but in any event it will be apparent that the soaking of the material, especially in the case of linen, takes place in the manner usual in an ordinary washing machine, even though the openings for readmitting the liquid into the cone are not partly stopped up by the material. The arrangement 35 of the parts, as above described, prevents any scorching of the material, since it is contained in drum 1 which is itself partly submerged in the liquid, so that it can never come into direct contact with the heater. The drum may, of course, be perforated over its entire surface.

At the completion of the operation, it is merely necessary to detach injector 14 from the cone neck or throat 13, after having first removed cover 24 and opened charging door 5, then close said door and, after having turned the drum through a half-revolution, the injector door 4, and then rotate the drum; such rotation preferably being carried out first in one direction and then in the other for a few revolutions. During rotation, the baffles 6 inside the drum will pick up the material and then drop it back into the liquid so that washing is rapidly effected; the washing being further facilitated in that the material has already undergone a bucking or scalding treatment and can be washed immediately thereafter, before it has had time to cool, and even in the scalding liquid itself. Moreover, the rapidity of the washing can be increased still further by leaving the machine on the heater, so that the cone neck 13 will then serve as an injector, stirring up the liquid and activating the treatment.

For rinsing, the washing liquid is discharged through drain cock 22, and rinsing

liquid is admitted through spout 19, whereafter the drum is rotated for a few moments. The rinsing liquid may be fed in a continuous stream through said spout and, after serving its purpose, may escape through overflow 23; or its escape may take place, if preferred, either through cock 22 (which has first been suitably adjusted to control its delivery) or through both parts 23 and 22. Centrifuging of the material can be simply effected by discharging the liquid through the drain cock, which is then left open, and rotating the drum rapidly for a few moments, the liquid contained in the material being driven out through the perforations 2 of the drum and falling into the outer vessel or container 10, whence it is discharged through the drain cock. These operations can, of course, be carried out without any handling of the material, as will be apparent; and it is advisable, during them, to keep the container closed in order to minimize heat losses and to avoid projection of liquid, especially during centrifuging.

It is to be noted that the machine above described may be used, if desired, solely as a bucking and scalding machine, either by putting the material to be treated in drum 1, as set forth, or by removing the drum and putting the material directly in container 10 as is usual in ordinary scalding machines. In the latter case, a perforated false bottom or screen 26 (Fig. 7) may be supported fixedly or detachably in the container in any suitable manner so as to keep the material a distance away from the bottom of the container in order to prevent it from being scorched, the presence of this screen entailing no change in the operation and offering no interference therewith. Furthermore, on removing the injector 14, and the cone 11 as well, if desired, the material can be placed in drum 1 and the latter then rotated in hot or boiling liquid, like an ordinary washing machine.

Figs. 4, 5 and 6 of the drawings show various other forms of bottom members and injectors which can be used. In Fig. 4, the bottom member 11', instead of having the shape of a cone, is formed by an inclined plate, with a throat or tubular stem 13' at its upper side. The injector 14', which removably telescopes over said throat at its lower end, is so bent or shaped as to extend part way around the drum, sprinkling or spraying taking place through the jet apertures 15'. The charging door 5 is removed, of course, to permit the injector end to project into the drum through the door opening and thus permit the sprinkling action to take place, and the door or gate 4 and the injector opening 3 are done away with. Rotation of the drum merely requires the detachment of the injector from throat 13' and the subsequent closing of the charging door.

In the construction represented in Fig. 5, a conical or approximately conical bottom 11'

is used, having an inclined central stem or throat 13² for coaction with an injector 14² bent similarly to the one in Fig. 4. The free terminal portion of this injector projects 5 horizontally entirely across the charging door opening and is perforated longitudinally along its under side as at 15², sprinkling taking place through these perforations instead of at the end or tip of the injector. The latter can be disengaged from throat 13² and removed, and the charging door then closed when it is desired to rotate the drum.

Fig. 6 shows a further modification in which a conical bottom member 11³ is employed having a frusto-conical throat or stem 13³, while the drum is provided in its circumferential wall with a tapered sleeve or socket 27 which is rigidly secured in an opening therein and carries a grating or screen 28 at 20 its inner end. A tubular injector 14³, similar to that of Figs. 1-3, is removably fitted over throat 13³, but the gate or door 4 is omitted. The steam and boiling liquid escape from the cone 11³ and pass into and through the socket 25 27 and its grating and the injector 14³, spraying taking place at the top of the injector at 15³, as in the first form. The grating or screen 28 serves to prevent the material under treatment from falling out of the drum 30 through socket 27 while the drum is being rotated.

As regards the further modifications illustrated in Figs. 7 to 12, Fig. 7, as has been stated, shows a perforated screen or grating 35 for supporting the material. Fig. 8 represents an arrangement in which an auxiliary siphon 29, provided with a cap 30, is utilized to increase the siphon effect produced by the injector and the openings 12 in its bottom member 11, as well as to prevent the escape 40 through said openings of the small quantity of steam which is generated at or near the same; in order to do so, such steam would have to lift, through the intermediary of the 45 siphons, of which there is one for each opening, the whole liquid column *a*. Fig. 9 shows the use of a bent tube 31 as a substitute for siphon 29-30.

In Fig. 10, a simpler form of siphon device 50 is illustrated, according to which the openings 12 in the bottom member or base 11 are provided with short depending tubes 32; these tubes, however, not preventing the escape of the steam generated directly beneath them. The openings or opening 12 (for there may be 55 only one such opening if preferred) may be equipped with flap valves 33 (Fig. 11) or ball valves 34 (Fig. 12); the valves admitting liquid in the direction of arrow *d'* but preventing steam and liquid from passing through 60 in the opposite direction. Finally, the bottom wall of the container may be provided with a baffle, fixed or removable, as indicated at 35 in Fig. 10, for the purpose of avoiding 65 leakage of steam through any interstices

which may exist between the bottom member or base 11 and the bottom wall of the container. Such baffle, however, can be constituted by a simple rib formed in or on said bottom wall and designated 36 in Fig. 11. It 70 will be observed from Figs. 10-12 that the bottom member or base can have a simple convex formation instead of being a true cone.

Figs. 13-15 show some forms which the injector may take: Fig. 13 represents a tapering tube 14⁴ provided at its top with a plate 16⁴ that leaves between it and the tube end a space 15⁴ for the discharge of the jets of steam and liquid therethrough; Fig. 14 illustrates a cylindrical tube 14⁵ topped with a mushroom head 16⁵ provided with jet openings or slots 15⁵; and Fig. 15, a tapering tube 14⁶ terminating in a mushroom head 16⁶ having jet holes 15⁶.

As will now be understood, the machine described and shown is fully adapted for bucking, scalding, washing, rinsing and centrifuging the material to be treated, and all this without said material having to be removed 90 from the machine and without any accessory handling being required. It is particularly well suited for scalding, washing, rinsing and centrifuging linen, the required lye and soap having, of course, first been put in the water 95 contained in the machine.

Taking as an example the washing of linen, the following operations can be carried out successively with the machine:

1. *Bucking*—(soaking).—Put the linen in 100 the drum and water in the container so that the linen will be thoroughly saturated, and let soak.

2. *Scalding*.—Empty the bucking water, put some water in the container, as well as 105 the usual scalding and lye-washing ingredients, and then put the machine on a heater and allow it to operate as a scalding machine.

3. *Washing*.—When the scalding has been completed, withdraw the injector, shut charging door 5, revolve the drum half a revolution, put in a plug or shut gate 4, then revolve the drum slowly for a few minutes, preferably a few revolutions in one direction and a few revolutions in the opposite direction, alternately.

4. *Rinsing*.—Drain off the washing water and replace it with clean water which may, if the rinsing is made in running water, enter in a continuous stream through spout 19, running off after having been used through overflow 23 or through cock 22, (the delivery of the latter having, of course, been suitably adjusted) and revolve the drum a few revolutions.

5. *Bleaching*—(Javelle water or chloride of potash treatment).—The required quantity of clean water being in the machine, pour in the Javelle water (chloruretted water) and revolve the drum a few revolutions.

6. *Blueing*.—The proper quantity of clean water being in the machine, put in the blueing and revolve the drum a few revolutions.

7. *Centrifuging*.—Container 10 having been emptied, all that is required to effect centrifuging is to revolve the drum rapidly for a few moments; the water contained in the linen escapes through holes 2 and flows out through cock 22. All these operations 10 are effected without the linen having to be handled.

I claim as my invention:

1. A washing machine, comprising an outer receptacle to contain washing liquid 15 adapted to be supported upon a heater; a perforated drum to contain the material to be washed journaled horizontally in said receptacle and having an opening in its side wall a perforated funnel-shaped bottom member 20 arranged in the receptacle and having a neck which underlies the opening in the drum; an injector removably fitting at its lower end on said neck and projecting upward into the upper portion of the drum, said injector holding said drum against rotation when in place, but permitting rotation when removed; a 25 gate slidably carried by the drum for closing said opening; and means for rotating said drum.

30 2. A washing machine, comprising an

outer receptacle to contain washing liquid adapted to be supported upon a heater; a perforated drum to contain the material to be washed journaled horizontally in said receptacle and having an opening in its side wall; a funnel-shaped bottom member arranged in the receptacle, having circulation openings for the liquid and also having an upwardly extending neck; an injector having its lower end removably and telescopically fitted on 40 said neck and its upper end projecting into the upper portion of the drum, said injector holding said drum against rotation when in place, but permitting rotation when removed; and means for rotating said drum. 45

3. A washing machine, comprising an outer receptacle to contain washing liquid adapted to be supported upon a heater; a perforated drum to contain the material to be washed journaled horizontally in said receptacle; a perforated funnel-shaped bottom member arranged in the receptacle and having an upwardly directed neck; a removable injector within the drum having its lower end in communication with said neck to receive boiling liquid and steam from said bottom member; and means for rotating said drum when said injector has been removed. 50 55

In testimony whereof I affix my signature.

LOUIS EUGÈNE CLÉMENCET.
